WELL CASING PERFORATOR

Filed June 26, 1939

INVENTOR:—
MILIO F. ALOI.
BY Martin P. Smith, ATTY.

UNITED STATES PATENT OFFICE

2,202,887

WELL CASING PERFORATOR

Millio F. Alois, Maywood, Calif.

Application June 26, 1939, Serial No. 281,214

13 Claims. (Cl. 164—0.5)

My invention relates to a well casing perforator of the gun type and has for its principal object, the provision of a relatively simple and practical casing perforating device including a body that is adapted to be lowered into well casing to the desired depth and, said body carrying a plurality of projectiles and an explosive charge which when ignited by an electric spark fires said projectiles outwardly through the wall of the casing, thereby perforating the same and, said projectile carrying body carrying means for producing the electric spark required to fire the explosive charge, thus eliminating all electrical connections between the gun-like member that is lowered into the casing and the ground surface at the top of the well hole.

A further object of my invention is, to provide simple and convenient means, preferably a weight that is permitted to slide by gravity downward on the cable that is utilized for lowering the perforator into the casing and which weight is effective in imparting motion to the electric spark producing means carried within the perforator so as to effect the firing of the explosive charge.

A further object of my invention is, to provide simple and efficient means for rendering the explosive charge firing means ineffective so as to prevent accidental or premature firing of the charge while the perforator is being assembled and made ready to be lowered into the casing.

With the foregoing and other objects in view, my invention consists in certain novel features of construction and arrangement of parts that will be hereinafter more fully described and claimed and illustrated in the accompanying drawing in which:

Fig. 1 is a vertical section taken through the center of a casing perforator constructed in accordance with my invention.

Fig. 2 is an elevational view of the upper end portion of the perforator and looking in the direction indicated by the arrow 2 in Fig. 1.

Fig. 3 is a plan view of the perforator.

Fig. 4 is a vertical section taken through the center of the weight that is utilized for effecting operation of the electric spark producing means.

Fig. 5 is a horizontal section taken on the line 5—5 of Fig. 4.

Fig. 6 is an enlarged horizontal section taken on the line 6—6 of Fig. 1.

Fig. 7 is an enlarged vertical section taken on the line 7—7 of Fig. 3.

Fig. 8 is an enlarged vertical section of the lower end portion of the perforating device.

Referring by numerals to the accompanying drawing which illustrates a preferred embodiment

of my invention, 10 designates a body, preferably cylindrical in form and composed of metal and which may be of any desired and convenient length. The diameter of this body is such that it will readily pass downward through oil well casing of standard sizes.

Formed in the upper portion of body 10 is a chamber 11 and, leading from the lower end of said chamber to the lower end of body 10 is an axial bore 12.

A head 13 is removably seated, preferably by being screw seated in the upper portion of chamber 11, and removably seated in the center of this head is a socket 14 to which is suitably connected, the lower end of a cable 15 that is utilized in lowering the perforator into the casing.

Arranged to slide freely through a vertically disposed bore 16 that is formed through head 13 to the side of socket 14, is a plunger 17, the upper end of which is enlarged to form a head 18 through the central portion of which is formed an aperture 19. An expansive spring 20 surrounds the upper portion of plunger 17 and bears against the lower end of the head 18 and against a shoulder 21 that is formed in the upper portion of the bore 16, thus normally maintaining the plunger in elevated position.

Plunger 17 passes through a fluid pressure tight gland or stuffing-box 22 that is arranged in the lower portion of head 13 and, that portion of the plunger that projects below said gland is provided with rack teeth 23. These teeth engage the teeth of a pinion 24, which latter is fixed on the armature shaft of a conventional magneto 25.

While plunger 17 is in its normal position or at the upper end of its limit of movement, the teeth of pinion 24 engage the lowermost teeth of rack 23. An opening formed in the wall of body 10 surrounding chamber 11 directly opposite the central portion of the magneto and which opening is closed by a readily removable plug 26, gives access to the magneto for the purpose of inspection, adjustment, repairs, etc.

Removably positioned in the aperture 19 in head 18 is a pin or key 27 that serves to secure the plunger in its elevated position and prevent the same from being accidentally moved downward to operate the magneto while the perforator is being charged and made ready for use and before it is inserted in the upper end of the well casing.

Formed through that portion of the perforator body 10 through which the bore 12 passes are radially disposed apertures 28, preferably disposed in spaced and staggered relation and which serve

55

as chambers for the bullet-like projectiles 29 that are utilized in perforating the casing. Formed within these chambers near their inner ends are shoulders 30 against which the rear ends of the 5 projectiles engage when properly positioned in the chambers.

The outer ends of the chambers 28 are closed by thin discs 31, preferably of metal that are pressed into recesses 32 that are formed in body 10 10 around the outer ends of the chambers 28.

Bore 12 is adapted to receive a cartridge comprising a thin walled casing 32 containing a charge 33 of explosive substance, such as gun powder. Embedded in the explosive charge 33 15 is a plate 34 of insulating material, carrying a pair of spaced spark terminals 35. The upper one of these terminals is connected by a conductor 36 to a contact 37 that is seated in the top of casing 32 and, when the casing is properly positioned in bore 12 this contact 37 directly engages a contact 38.

This contact 38 is carried by the lower end of a pin or rod 39 formed of metal and serving as a conductor for electric current and, which passes 25 through that portion of the body 10 between the upper end of bore 12 and the lower portion of chamber 11. This conductor 39 is suitably insulated from the metal in body 10, preferably by a sleeve 40 of insulating material.

30 One side of the magneto 25 is grounded on the body 10 while the other side is connected by a conductor 41 to the upper end of conductor 39.

The lower end of the cartridge receiving bore or chamber 23 is closed by a screw plug 42, there 35 being a packing ring or gasket 43 arranged between the upper portion of said plug and the body 10 around the lower end of bore 12 and, arranged for sliding movement in the upper portion of this plug is an axially arranged pin 44 40 provided on its upper end with a head 45. An expansive coil spring 46 is arranged between the head 45 of contact pin 44 and a shoulder 47 that is formed in the upper portion of plug 42 around the aperture that receives said contact 45 pin.

Seated in the lower end of the cartridge that is positioned in bore 12 is a contact pin 48 provided on its lower end with a head 49 and, which latter engages the head 45 of the spring-held 50 contact pin 44.

Connecting contact pin 48 with the lower one of the spark terminals 35 is a conductor 50.

The means utilized for forcing plunger 17 downward to operate the magneto is illustrated in 55 Fig. 4 and 5 and comprises a two-part weight 51 substantially cylindrical in form and, the two parts of which are hingedly connected to each other, preferably by a vertically disposed hinge pin 52. The two parts of the weight are normally 60 held in closed position by means of a hook 53 that is hinged to one of the parts of the weight and which engages in a recess 54 in the other part (see Fig. 5). Formed in the lower portion 65 of this weight is a chamber 55 open at its lower end and which is of such size as to receive the socket 14 and, formed through the upper portion of said weight is an axial opening 56 that receives the cable 15 that carries the perforator.

70 To load the perforator, key 27 is inserted through opening 19 in head 18 so as to prevent the plunger from being moved downward to operate the magneto and the projectiles 29 are now inserted in their chambers 28, after which the 75 disc-like closures 31 are pressed into the recesses

32, thereby closing the projectile containing chambers.

The explosive cartridge is now inserted in bore 12 and plug 42 is screw seated in the lower end of body 10 and, when so seated the spring-held 5 contact 46 engages contact 48 on the lower end of the cartridge and the latter is maintained in the bore 12 with contact pin 37 in engagement with contact 38.

Just before the perforator is lowered into the 10 casing, the key 27 is removed from head 18, thus leaving plunger 17 free to move downward as a result of the engagement of the weight 51 with said head at the termination of its travel down the cable 15.

The perforator is now lowered into the well casing by proper manipulation of cable 15 and, when said perforator has reached the depth at which the casing is to be perforated, the two-part weight 51 is opened and after being applied to 20 the cable the parts of the weight are closed and held in such position by the engagement of the free end of hook 53 in recess 54.

The weight is now released and by gravity it 25 will slide down the cable from which the perforator is suspended and, when the weight reaches the upper end of the perforator it will strike the top of head 18, thereby moving the same and plunger 17 downward and, the engagement of the 30 rack 23 with pinion 24 will actuate the armature of the magneto so as to produce an electric spark between the terminals 35. As the spark is produced between the sparking terminals, the explosive charge of the cartridge will be fired and 35 the resulting force will drive the projectiles 29 outwardly from their chambers through the adjacent wall of the casing so as to perforate the same, thereby accomplishing the desired results.

After the casing operation as just described has 40 been accomplished, the perforator is withdrawn from the well by means of cable 15 and said perforator may be re-used after the chambers 25 have been refilled with projectiles and a cartridge inserted in bore or chamber 12.

A particularly advantageous feature of my improved perforator is the mounting of a magneto or other spark producing means within or directly upon the perforator, for by such provision the requirement for spark producing means including electrical conductors extending from the top of the well hole downwardly therethrough to the perforator and which distance may be several thousand feet, is entirely eliminated.

Thus it will be seen that I have provided a casing 55 perforator that is relatively simple in construction, inexpensive of manufacture and very effective in performing the functions for which it is intended.

It will be understood that minor changes in the 60 size, form and construction of the various parts of my improved well casing perforator, may be made and substituted for those herein shown and described, without departing from the spirit of 65 my invention, the scope of which is set forth in the appended claims.

I claim as my invention:

1. A casing perforator comprising a body provided with a chamber for the reception of an explosive charge, there being chambers formed in the body for directing the force of the exploded charge laterally against the well casing in which the perforator is positioned, projectiles located in said last mentioned chambers and magnets actuated means located wholly within said body and 70

operable from the exterior thereof for producing an electric spark within the explosive charge.

2. In a casing perforator the combination with a body, of a cable connected to said body for lowering the same into well casing, an explosive charge contained within said body, there being chambers formed in the body for directing the force of the exploded charge laterally toward the well casing, projectiles located in said chambers, 5 magneto actuated means carried by the body for producing an electric spark in the explosive charge and means adapted to slide down the cable to said body for actuating the spark producing means.
- 10 3. A casing perforator as set forth in claim 1, with means for rendering the spark producing means inoperative while the body is being loaded for use and before it is lowered into the well casing.
- 15 4. In a casing perforator, a body adapted to be lowered into well casing, an explosive charge contained within said body, there being chambers contained in said body for directing the explosive force of said charge laterally toward the surrounding well casing and means including a magneto carried by said body for producing an electric spark in said explosive charge.
- 20 5. In a well casing perforator the combination with a body, of a cable connected to said body for lowering the same into well casing said body containing an explosive charge, there being chambers formed in said body for directing the force of the exploded charge toward the well casing surrounding said body, projectiles in said chambers, means including a magneto carried by said body for producing an electric spark in said explosive charge and a member adapted to travel downward on the cable that carries said body for actuating said magneto.
- 25 6. A well casing perforator as set forth in claim 5 and with means for rendering the spark producing means inoperative while the body is being made ready for use and before being lowered into the casing.
- 30 7. In a well casing perforator, a body, an explosive charge contained within said body, there being chambers formed in said body for directing the explosive force of said charge outwardly toward the well casing in which the body is suspended, projectiles located in said chambers, a pair of spaced ignition points located in said explosive charge and means carried by the body for

generating an electric current and causing the same to pass through said ignition points and the spark gap between the same.

8. A casing perforator as set forth in claim 7, with a cable connected to said body for lowering the same into well casing and means adapted to travel downwardly upon said cable for actuating said spark producing means.

9. In a well casing perforator, a body, an explosive charge contained within said body, there being chambers formed in said body for directing the explosive force of said charge outwardly toward the well casing in which the body is suspended, projectiles located in said chambers, a pair of spaced ignition points located in said explosive charge and means including a magneto carried by the body for generating an electric current and causing the same to pass through said ignition points and the spark gap between the same.

10. A well casing perforator as set forth in claim 9, with a cable connected to said body for lowering the same into well casing and means adapted to travel downwardly upon said cable and to actuate the magneto of said spark producing means.

11. In a well casing perforator, a gun body including a plurality of gun units arranged to discharge laterally from said body, said gun units including an explosive charge receiving chamber and a plurality of projectile receiving chambers that communicate with the explosive charge receiving chamber, an electric circuit including a pair of spaced spark terminals located within the charge occupying said explosive charge receiving chamber and magneto means carried by said gun body for energizing said circuit and producing an electric spark between said spaced spark terminals.

12. A well casing perforator as set forth in claim 11 and with means for actuating said magneto means from the exterior of said perforator.

13. In a well casing perforator, a body provided with a chamber for the reception of an explosive charge, said body being provided with a plurality of projectile receiving chambers that communicate with the explosive charge chamber and magneto means carried by said body for producing an electric spark within the charge located within said explosive charge receiving chamber.
